United States Patent [19]

Ioffe et al.

[11] Patent Number: Des. 297,168

[45] Date of Patent: ** Aug. 9, 1988

[54] TRANSCUTANEOUS ELECTRICAL NERVE STIMULATOR

[75] Inventors: Zosim Ioffe, St. Paul, Minn.; Stephen H. Ober, Salt Lake City, Utah; Donald D. Maurer, Anoka, Minn.

[73] Assignee: Empi, Inc., St. Paul, Minn.

[**] Term: 14 Years

[21] Appl. No.: 754,355

[22] Filed: Jul. 12, 1985

[52] U.S. Cl. D24/41; D24/36; D24/40

[58] Field of Search ..... D24/36, 40, 41; 128/419 R, 419 P, 421, 422

[57] CLAIM

The ornamental design for a transcutaneous electrical nerve stimulator, as shown and described.

DESCRIPTION

FIG. 1 is a perspective view of a transcutaneous electrical nerve stimulator showing our new design;

FIG. 2 is a front elevational view thereof;

FIG. 3 is a rear elevational view thereof;

FIG. 4 is a side elevational view as seen from the side opposite that shown in FIG. 1;

FIG. 5 is a side elevational view as seen from the side opposite that shown in FIG. 4;

FIG. 6 is a top plan view thereof; and

FIG. 7 is a bottom plan view thereof.
